UNITED STATES PATENT OFFICE

2,463,910

PIANO PEDAL EXTENSION DEVICE

Jean Oskar Rydstrom, Glenview, Ill.

Application February 24, 1947, Serial No. 730,310

5 Claims. (Cl. 84—230)

1

This invention relates to a pedal extension device for pianos.

The principal object of the invention is to provide an extension device for piano pedals which may be used by children and other people of short stature who are unable to reach piano pedals from a normal sitting position.

A further object is to provide such a device which may be readily secured to a piano in operative relationship to the piano pedals.

A further object is to provide such a device which has a foot rest of sufficient area to accommodate the feet, and the pedal members of which may be adjusted to various heights above the foot rest.

A further object is to provide such a device which may be used with pianos having varying spacings between the pedals.

A further object is to provide such a device which assures that a child learning to play the piano will place his feet in substantially the same position that they will assume when he has attained his growth.

A further object is to provide such a device which is composed of simple parts, which is easy to adjust and which presents a neat appearance.

The invention is illustrated in a preferred form in the accompanying drawings, in which:

Fig. 1 is a plan view of the device in position above the pedals of a piano; Fig. 2 is a rear elevation thereof, partially in section; and Fig. 3 is an end elevation, viewing Fig. 2 from the left, partially in section.

Referring to the drawings in greater detail, the device consists of a foot rest 4 which is generally horizontally disposed, and which has a plane surface of sufficient area to accommodate the feet. Supporting means for the foot rest are provided by a plurality of legs 5, the length of which may be adjusted by means of screws 6, having their heads furnished with pads 7.

A child learning to play the piano very seldom has occasion to use the center pedal thereof. Accordingly, my device is provided with a fastening member, indicated generally at 8, by which it may be secured to the center pedal 9 of a piano. This fastening member consists of a vertically adjustable element 10, preferably a long bolt extending through an aperture in the foot rest 4, and vertically adjustable with respect thereto by means of a wing nut 11. A pedal engaging portion 12 is provided at the lower end of the bolt 10, this portion preferably being in the form of a flattened stirrup which may be drawn into frictional engagement with the un-

2

derside of the pedal 9 by adjustment of the wing nut 11.

Identical pedal member supports 13 are secured to the rear margin of the foot rest 4 by means of bolts 14 extending through vertical slots 15 in the support 13, and horizontal slots 15a in the foot rest 4; the bolt and slot arrangement permitting vertical and horizontal adjustment of the pedal member supports with respect to the foot rest 4. Forwardly extending pedal members 16 are pivotally secured adjacent the upper ends of the pedal supports 14 by means of hinges 17 and extending forwardly therefrom, each of the pedal members 16 preferably being of the same shape as the corresponding outer pedal of a conventional piano.

The foot rest 4 accommodates a pair of push rods 18, each of which is mounted in a laterally elongated aperture 18a beneath one of the pedal members 16. Each push rod consists of a bushing 19 which is locked in its aperture 18a by means of a lock nut 19a, an interiorly threaded tube 20 slidably mounted in the bushing 19, a top pad 21 secured to the upper end of the tube 20 and adapted to contact the underside of the pedal member 16, and an extension member 22 secured in the lower end of the threaded tube 20, the extension member 22 preferably being provided with a rubber foot 23 which rests upon a piano pedal 24. The extension member 18 is furnished with a wing nut 25 by which it may be locked in position in the tubular member 20. A coil spring 26 is mounted on the tube 20 between the bushing 19 and the pad 21, so as to relieve the return springs (not shown) of the piano pedals 24 of the weight of the pedal members 16 and push rods 18.

The use of my device is obvious from the foregoing description. The device is placed in position in front of the piano, and the height of the foot rest is arranged to suit the leg length of the pianist by adjustment of the screws 6. The pedal engaging member 12 is then hooked beneath the middle pedal 9 of the piano and drawn tightly against it by screwing up the wing nut 11. The push rods 18 are adjusted to register with the piano pedals 24 by sliding the bushings 19 in the slots 18a and locking them in place by means of the lock nuts 19a, after which the pedal members 16 may be brought into register with the push rods by adjusting the screws 14 in the slots 15a. The pedal members are set at the desired height by appropriate vertical adjustment of the pedal member supports 13 with respect to the screws 14, the latter then being tightened to re-

tain the desired horizontal and vertical adjustment of the pedal members. Lastly, the push rods 18 are adjusted to rest lightly upon the piano pedals 24 by setting the adjustment members 22 in suitable positions. Ordinarily the device will always be used with the same piano, so that adjustment of the pedal members and push rods will be infrequent.

While I have shown and described a specific embodiment of my invention, it is to be understood that it is capable of many modifications. Changes, therefore, in the construction and arrangement may be made without departing from the spirit and scope of the invention as disclosed in the appended claims.

I claim:

1. A piano pedal extension device, comprising: a foot rest having a substantially horizontal plane surface of sufficient area to accommodate the feet; means for supporting said foot rest; a fastening member by which the device may be secured to a piano; a pedal support secured to the rear edge portion of the foot rest, said support extending above said foot rest and being vertically adjustable with respect thereto; a pedal member pivotally secured adjacent to the upper end of said pedal support and extending forwardly therefrom; and means for transmitting motion from said pedal member to the pedal of the piano.

2. A piano pedal extension device, comprising: a foot rest having a substantially horizontal plane surface of sufficient area to accommodate the feet; means for supporting said foot rest; a fastening member by which the device may be secured to a piano; a pedal support secured to the rear edge portion of the foot rest, said support extending above said foot rest and being vertically adjustable with respect thereto; a pedal member pivotally secured adjacent the upper end of said pedal support and extending forwardly therefrom; and a push rod slidably mounted in an aperture in the foot rest beneath said pedal member, said push rod furnishing at least part of the support for the pedal member; and a compression spring interposed between the pedal member and the foot rest.

3. A piano pedal extension device, comprising: a foot rest having a substantially horizontal plane surface of sufficient area to accommodate the feet; means for supporting said foot rest; a fastening member by which the device may be secured to a piano; a pedal support secured to the rear edge portion of the foot rest, said support extending above said foot rest and being vertically adjustable with respect thereto; a pedal member pivotally secured adjacent the upper end of said pedal support and extending forwardly therefrom; a bushing mounted in an aperture in the foot rest beneath said pedal member; a threaded member slidably mounted in the bushing; a pad secured to the top of said threaded member, said pad being adapted to serve as a support for the pedal member; and an adjustment member screwed to the lower end of the threaded member.

4. A piano pedal extension device, comprising:

a foot rest having a substantially horizontal plane surface of sufficient area to accommodate the feet; vertically adjustable means for supporting said foot rest; a vertically adjustable element depending from said foot rest; a stirrup-like pedal engaging portion at the lower end of said element adapted to hook beneath a piano pedal and make frictional engagement therewith; a pedal support extending above the foot rest and vertically and horizontally adjustable with respect thereto; a pedal member pivotally secured adjacent the upper end of said pedal support; a bushing adjustably mounted in a laterally elongated aperture in the foot rest beneath said pedal member; a threaded member slidably mounted in said bushing; a pad secured to the top of said threaded member, said pad being adapted to serve as a support for the pedal member; an adjustment member screwed to the lower end of the threaded member; and a compression spring mounted between said bushing and said pad.

5. A piano pedal extension device comprising: a foot rest having a substantially horizontal plane surface of sufficient area to accommodate the feet; a plurality of supporting members for said foot rest, said supporting members being independently vertically adjustable; a vertically disposed and longitudinally adjustable pedal engaging anchor member depending from the foot rest, said member having a stirrup-like portion at its lower end adapted to hook beneath a piano pedal to anchor the foot rest thereto; a pedal support secured to the rear edge portion of the foot rest by means of a threaded bolt extending through a pair of perpendicularly opposed slots in said support and said edge portion so as to permit horizontal and vertical adjustment of the pedal support; a bushing adjustably mounted in a laterally elongated aperture in the foot rest beneath said pedal member; a threaded member slidably mounted in said bushing; a pad secured to the top of said threaded member, said pad being adapted to serve as a support for the pedal member; an adjustment member screwed to the lower end of the threaded member; and a compression spring mounted between said bushing and said pad.
